UNITED STATES PATENT OFFICE.

CHARLES A. PSILANDER, OF EASTON, PENNSYLVANIA, ASSIGNOR TO WILLIAM WHARTON JR. & CO., INCORPORATED, OF EASTON, PENNSYLVANIA, A CORPORATION OF PENNSYLVANIA.

METHOD AND MEANS FOR MAKING COMPROMISE ANGLE BARS.

Application filed July 1, 1922. Serial No. 572,242.

To all whom it may concern:

Be it known that I, CHARLES A. PSILANDER, a citizen of the United States, residing at Easton, in the county of Northampton and State of Pennsylvania, have invented certain new and useful Improvements in Methods and Means for Making Compromise Angle Bars, of which the following is a specification.

10 This invention provides a method and means for effecting variable offsetting of bars and the like, for example, compromise bars or fish bars of straight or angular form.

In making compound joints, for example 15 so-called compromise bars it is often necessary to offset the upright and foot portions, and this operation has heretofore been done in two distinct steps. Moreover, since it is often necessary to provide the upright and 20 foot portions with different degrees of offsets, the two step operation is a substantial doubling of the time and labor required for a single bend or offset.

According to my invention, both the 25 upright and foot portions of the bar are simultaneously offset laterally in a single pressure movement, and the relative degrees of offset as between such portions may be varied at will.

30 The invention provides novel apparatus for use in conjunction with, for example, a bulldozer, so that any desired degree of offset may be provided in the foot or upright, and any relative degree of offset in both the 35 foot and upright, the offsetting being effected in a single pressure movement.

The apparatus for the performance of my invention preferably includes co-axially mounted and longitudinally split or partible barrel dies. The two elements of the respective dies are interiorly shaped to snugly receive the bar to be offset. The dies are mounted for rotative adjustment between spaced jaws in a bulldozer or equivalent machine. The jaws are so constructed and arranged as to be capable of limited movement in the respective heads of the bulldozer or other machine, liners being interposed between the jaws and heads to control 45 the desired offsetting operation. Thus it will be understood that when the jaws close upon the dies in response to pressure of the

heads, the dies will have an angular movement determined by the relative thickness of the liners employed. This evidently results 55 in a corresponding offset in the bar.

The invention contemplates the offsetting of both hot and cold bars, but as more pressure of course will be necessary for cold bending and it is desirable to use the ordinary bulldozer, the bars are preferably heated, and any character or degree of offsetting effected at one heat.

In the accompanying drawings,—

Figure 1 is an end elevation of an apparatus embodying my invention.

Fig. 2 is a central transverse section.

Fig. 3 is a plan view.

Fig. 4 is a longitudinal section on line 4—4 of Fig. 3.

Fig. 5 is a perspective view of one of the barrel dies in open position.

Fig. 6 is a perspective view of the carriage on which the dies are mounted.

Fig. 7 is a perspective view of a section 75 of a splice bar having vertical and lateral offsets produced in accordance with my invention.

That part of the apparatus through which the improved method is carried out involves 80 a series of (in this example two) barrel shape or cylindrical dies 1 and 2, each constructed of longitudinally co-operating sections 3 and 4. The proximate faces of the die sections are formed as at 5, to receive 85 a bar 6, and the respective halves of each die are hingedly connected at their outer ends by U form brackets 7, pivotally connected by bolts 8, at points remote from the die proper, in order to permit a full opening 90 of each die. The barrel dies are recessed as at 9, and provided with coincident openings 10, for the reception, if necessary, of suitable locking provisions.

Each barrel die is mounted on inner and 95 outer carriage trucks 11 and 12, the inner truck being beneath the inner or adjacent ends of the barrel dies and the outer trucks at the outer ends thereof. The inner trucks carry truck supporting rollers 13 and die supporting rollers 14, while the outer trucks carry truck-supporting rollers 15 and die-supporting rollers 16. The outer trucks are also provided with an upstanding flange 17

formed with a series of variable graduated holes 18, the flange 17 of the outer truck overlying the outer ends of the barrel dies. The ends of the barrel dies are also formed 5 with openings 19, preferably in the upper and lower series, so that any of the openings 19 may be brought into registry with the openings 18 of the flange 17, for the reception of pins to hold the barrel dies in 10 any position of rotative adjustment desired, the purpose of which will later appear. The trucks are secured relatively by rods *a* passing through elongated slots *b* in the inner trucks and having threaded terminals to 15 receive lock nuts *c, d*. The rods are formed so as to have a certain degree of spring quality or flexure in order to permit relative movement of the trucks in the offsetting movement of the dies, and the elongated 20 slots *b* facilitate the return of the parts to normal position. In addition to the adjustment afforded by the lock nuts *c, d*, the inner trucks may be spaced by the provision of 25 separators *e* carried by the rods, the separators, when present, operating in conjunction with cotter pins *f*.

The barrel dies are each held between opposing jaws 20, 21, having a limited sliding connection as by bolt and slot connector 22, with the heads 23 and 24 of a bulldozer or other similar machine. The jaws have thus a limited independent movement in the heads, one of which heads is usually stationary, and the other movable under pressure.

Liners 25 of varying thickness are employed with the apparatus, these liners being interposed between the jaws 20, 21, and the heads 23, 24. Obviously, if a thin liner 40 is employed behind the jaw 20 of one barrel die and a thick liner behind the jaw 21 of the same barrel die, and this arrangement be reversed with respect to the other barrel die, then when the jaws are brought together onto the dies, the latter will be offset a distance equal to the difference between the thick and thin liners. Therefore, 45 the offset depends upon the relative thickness of the liners employed, so that the machine readily lends itself to any degree of offset which may be found necessary. The truck or carriage on which the dies are mounted is so constructed as to have a certain amount of flexure which provides for 50 more or less tolerance between the sets of dies. There is also a slight difference, say one-sixteenth of an inch in the end openings of the dies and the complementary pin-receiving openings in the truck or cradle 55 forming a roller path for the dies. The barrel dies are properly spaced and shearing of the bar is prevented by distance adjusting screws 26.

If it is only necessary to offset the bar 60 in a vertical direction, as for instance a

bar for use between a new or full section and a worn section of rail, the vertical part of the bar should be in a horizontal plane as shown at A—A in Fig. 1. And if a lateral offset only is required, as for instance between two rails of different width heads but same fishing section, the barrel dies and the bar are adjusted so as to be at an angle of 90° to the line of pressure. Since both vertical and lateral offsets *x* 70 and *y* (Fig. 7) are required in compromise bars, the proper turning of the barrel will insure any proportions between the horizontal and vertical. For instance, if the vertical offset is three-eighths and the horizontal offset is three-thirty-seconds, the hypotenuse is the difference in the lining of the jaws, and this regulates or controls the angle to which the line A—A should be adjusted from the horizontal, either by turning the barrel clockwise or anti-clockwise according to whether a right or left hand joint is desired. The angle being determined, the dies are secured by pins 27 co-operating with the holes 18 and 19. If the 80 pin holes in the barrel are given a somewhat larger spacing, say one-sixteenth of an inch, than the holes in the carriage, a very close setting or adjustment can be provided for.

Having described my invention, I claim:

1. The method of shaping ordinary splice bars to adapt them for use as compromise bars to connect rails of different section, which consists in centering a splice bar in endwise disposed co-acting offsetting dies capable of selective rotative movement, establishing the requisite differential adjustment to control the character and degree of offset, and completing the operation by subjecting the dies conjointly to a single application of pressure.

2. The method of offsetting bars for use as compromise joints, which consists in 110 simultaneously and in a single pressure movement offsetting both the foot and upright portions of the bar, the relative degree of offsetting being determined by controlling the angular relation of the bar to 115 the line of pressure.

3. The method of offsetting bars for use as compromise joints, which consists in establishing the degree of offset by disposing the bar at an inclination to the line of pressure and applying pressure to the part to be offset.

4. The method of offsetting bars for use as compromise joints, which consists in independently supporting the parts to be offset, and varying the pressure responsive movements of the independent supports.

5. Means for effecting variable offsetting of straight bars, comprising, in combination, bar supporting means capable of turn-

- ing movement, means for arresting the turning movement for controlling the degree of offsetting, and means for applying pressure to the bar supporting means.
- 5 6. Means for effecting variable offsetting of straight bars, comprising, in combination, coaxial barrel dies shaped to suit the bar, a roller path for the dies and on which they are turnable to vary the angle of inclination to the line of pressure, means for fixing said angle, and means for applying offsetting pressure.
- 10 7. Means for effecting variable offsetting of straight bars, comprising, in combination, coaxial partible barrel dies shaped to accommodate the bar, a roller path for the dies and on which they are turnable to regulate the position of the bar with relation to the line of pressure, jaws co-operating with the dies, and means for exerting pressure through the jaws.
- 15 8. Means for effecting variable offsetting of straight bars, comprising, in combination, coaxial partible dies to support the bar, a roller path for the dies and on which they are turnable to regulate the position of the bar with relation to the line of pressure, jaws co-operating with the dies, means for lining up the jaws to control the offsetting operation, and means for applying pressure.
- 20 9. Means for effecting variable offsetting of straight bars, comprising, in combination, coaxially mounted bar holding dies, means for relatively securing them to prevent shearing of the bar, and means for shifting the dies in a circumscribed arc of movement to control the offsetting operation, and means for exerting pressure on the dies to perfect the offsetting.
- 25 10. Apparatus for the purpose specified, including independent means for supporting the respective ends of the bar in both directions beyond the offset line, and means for inducing variable relative movement of such independent means under a single pressure device.
- 30 11. Apparatus for the purpose specified, including independent means for supporting the respective ends of the bar in both directions beyond the offset line, a single pressure means, and means for causing said single pressure means to have a variable moving effect on such independent means.
- 35 12. Apparatus for the purpose specified, including independent means for supporting the respective ends of the bar in both directions beyond the offset line, means for rotatively supporting the independent means, and means for inducing variable relative movement of such independent means in the operation of a single pressure device.
- 40 13. Apparatus for the purpose specified, including independent means for supporting the respective ends of the bar in both directions beyond the offset line, means for rotatively supporting said independent means, means acting in a constant pressure line on said independent means without regard to the rotative movement thereof, and means whereby said single pressure means compels a variable relative movement of said independent means.
- 45 14. Apparatus for the purpose specified, including alined barrel dies within which the bar is secured, opposed pressure jaws co-operating with each barrel die, a head co-operating with each pair of jaws and relatively movable under pressure, and means whereby the jaws of one barrel die may be offset relative to the jaws of the other barrel die in the completed pressure movement of the heads.
- 50 15. Apparatus for the purpose specified, including alined barrel dies to receive the bar, opposed pressure jaws co-operating with each barrel die, a head co-operating with similar jaws of each die and relatively movable under pressure, the jaws being capable of relative movement with respect to the head, and liners to space the similar jaws of each die from the head to the variable extent indicated by the desired offset in the ultimate compromise bar.
- 55 16. Apparatus for the purpose specified, including alined barrel dies to receive the bar, a single pressure means adapted to successively engage and operate said dies to finally arrange the dies in axial offset relation, and means for mounting the dies for rotation to vary the angular relation of the foot and upright of the bar to the line of pressure.
- 60 17. Means for effecting multiple offsetting, comprising the combination of bar supporting means, means for mounting the bar supporting means for rotary movement, means for limiting the rotary movement to control the degree of offsetting, and means for applying pressure to the bar supporting means.
- 65 18. In combination with a bulldozer, jaws co-operating with the respective heads thereof, barrel dies mounted for turning movement between said jaws, means for lining up the jaws to determine the ultimate movement of the dies, and a roller path co-operating with the dies.
- 70 19. Means for effecting variable offsetting of bars and the like, comprising, in combination, bar supporting dies of external cylindrical form, a roller path on which said dies are adjustable in their axis of rotation, die blocks, means for adjusting them to control the offsetting operation, and means for positioning the dies in accordance with the adjustment of the blocks.
- 75 20. Means for effecting variable offsetting of bars and the like comprising, in combination, coaxial bar supporting dies of external cylindrical form, a roller path on which said dies are adjustable in their axis of rotation, die blocks, means for adjusting them to control the offsetting operation, and means for positioning the dies in accordance with the adjustment of the blocks.
- 80 21. Means for effecting variable offsetting of bars and the like comprising, in combination, coaxial bar supporting dies of external cylindrical form, a roller path on which said dies are adjustable in their axis of rotation, die blocks, means for adjusting them to control the offsetting operation, and means for positioning the dies in accordance with the adjustment of the blocks.
- 85 22. Means for effecting variable offsetting of bars and the like comprising, in combination, coaxial bar supporting dies of external cylindrical form, a roller path on which said dies are adjustable in their axis of rotation, die blocks, means for adjusting them to control the offsetting operation, and means for positioning the dies in accordance with the adjustment of the blocks.
- 90 23. Means for effecting variable offsetting of bars and the like comprising, in combination, coaxial bar supporting dies of external cylindrical form, a roller path on which said dies are adjustable in their axis of rotation, die blocks, means for adjusting them to control the offsetting operation, and means for positioning the dies in accordance with the adjustment of the blocks.
- 95 24. Means for effecting variable offsetting of bars and the like comprising, in combination, coaxial bar supporting dies of external cylindrical form, a roller path on which said dies are adjustable in their axis of rotation, die blocks, means for adjusting them to control the offsetting operation, and means for positioning the dies in accordance with the adjustment of the blocks.
- 100 25. Means for effecting variable offsetting of bars and the like comprising, in combination, coaxial bar supporting dies of external cylindrical form, a roller path on which said dies are adjustable in their axis of rotation, die blocks, means for adjusting them to control the offsetting operation, and means for positioning the dies in accordance with the adjustment of the blocks.
- 105 26. Means for effecting variable offsetting of bars and the like comprising, in combination, coaxial bar supporting dies of external cylindrical form, a roller path on which said dies are adjustable in their axis of rotation, die blocks, means for adjusting them to control the offsetting operation, and means for positioning the dies in accordance with the adjustment of the blocks.
- 110 27. Means for effecting variable offsetting of bars and the like comprising, in combination, coaxial bar supporting dies of external cylindrical form, a roller path on which said dies are adjustable in their axis of rotation, die blocks, means for adjusting them to control the offsetting operation, and means for positioning the dies in accordance with the adjustment of the blocks.
- 115 28. Means for effecting variable offsetting of bars and the like comprising, in combination, coaxial bar supporting dies of external cylindrical form, a roller path on which said dies are adjustable in their axis of rotation, die blocks, means for adjusting them to control the offsetting operation, and means for positioning the dies in accordance with the adjustment of the blocks.
- 120 29. Means for effecting variable offsetting of bars and the like comprising, in combination, coaxial bar supporting dies of external cylindrical form, a roller path on which said dies are adjustable in their axis of rotation, die blocks, means for adjusting them to control the offsetting operation, and means for positioning the dies in accordance with the adjustment of the blocks.
- 125 30. Means for effecting variable offsetting of bars and the like comprising, in combination, coaxial bar supporting dies of external cylindrical form, a roller path on which said dies are adjustable in their axis of rotation, die blocks, means for adjusting them to control the offsetting operation, and means for positioning the dies in accordance with the adjustment of the blocks.
- 130 31. Means for effecting variable offsetting of bars and the like comprising, in combination, coaxial bar supporting dies of external cylindrical form, a roller path on which said dies are adjustable in their axis of rotation, die blocks, means for adjusting them to control the offsetting operation, and means for positioning the dies in accordance with the adjustment of the blocks.

1
5
nal cylindrical form, means for spacing them, means for adjusting the dies to vary the angular relation of the bar to the line of pressure, a roller path for the dies, and means for controlling the adjustment of the dies.

21. Means for effecting variable offsetting of bars and the like, comprising in combination, cylindrical dies to receive the bar, a flexible carriage for the dies, a source of pressure, and means controllable at will for adjusting the dies so as to vary the angular relation of the bar to the line of pressure.

22. Means for effecting variable offsetting of bars and the like, comprising, in combination, co-acting barrel dies, means for variably offsetting said dies with relation to the line of pressure, and means for applying pressure to the dies.

20 23. Means for effecting variable offsetting of bars and the like, comprising co-acting barrel dies each formed of pivotally connected half-dies, a roller path for the dies, means for applying pressure to the dies, and means 25 controllable at will for effecting relative adjustments of the dies in a circumscribed arc of movement.

24. In a machine of the nature indicated, the combination of bar supporting and off- 30 setting dies, adjustable die blocks, and a roll-

ing support for the dies intermediate the blocks.

25. In a machine of the nature indicated, the combination of axially aligned bar supporting and offsetting dies, adjustable die 35 blocks, and liners co-operating with the die blocks to control the offsetting operation.

26. In a machine of the nature indicated, the combination of co-acting offsetting dies, means for controlling the offsetting opera- 40 tion, and a rolling support for relatively po- 45 sitioning the dies in accordance with such control.

27. In a machine of the nature indicated, the combination with heads one of which is 45 responsive to pressure, of co-operative bar supporting and offsetting dies, mounted for relative rotative adjustment, die blocks, and liners co-operating with said die blocks and heads to determine the relativity of the dies. 50

28. The method of offsetting bars for use as compromise joints, which consists in simultaneously and in a single pressure movement vertically and horizontally offsetting both the foot and upright portions of the 55 bar.

In testimony whereof I affix my signature.

CHARLES A. PSILANDER.
